CIRCUIT PROTECTION DEVICE

CROSS-REFERENCE TO RELATED APPLICATION

This application claims priority to and the benefit of Korean Patent Application No. 2019-0117006, filed on Sep. 23, 2019, the disclosure of which is incorporated herein by reference in its entirety.

FIELD

The present invention relates to a circuit protection device, and more particularly, to a circuit protection device configured to restrict an inrush current when an electronic product is initially driven and to prevent fire caused by an increase in internal temperature or an overcurrent.

BACKGROUND

In general, in an electric circuit of a large electronic product such as an air conditioner, a washer, a refrigerator, a dryer, or the like, a circuit protection device is provided at a power input terminal of the electric circuit and protects a power circuit to prevent a failure caused by an inrush current, an increase in internal temperature, a continuous overcurrent, and the like which occur when power is turned on.

FIGS. 1A and 1B illustrate components and operations of an existing circuit protection device. The existing circuit protection device includes a fuse resistor RF, a first relay S1 connected to the fuse resistor RF in a series, and a second relay S2 connected to the fuse resistor RF and the first relay S1 in parallel. The fuse resistor RF includes a resistor R and a thermal fuse F, and the resistor R and the thermal fuse F are connected to each other in series.

In the circuit protection device, state (a) in which the first relay S1 is closed and the second relay S2 is opened at a driving time is converted into state (b) in which the first relay S1 is opened and the second relay S2 is closed after a certain time.

In state (a), an input current passes through the fuse resistor RF and the first relay S1 and is input to an electrical circuit. Here, when the resistor R limits an inrush current to a certain current and an overcurrent flows thereto, heat generated by the resistor R is conducted to the thermal fuse F and a fused body including solid lead or polymer pellets provided inside the thermal fuse F is fused to short-circuit a circuit so as to protect an electrical circuit of a home appliance. After a certain time (for example, about 0.5 seconds) in which the inrush current disappears and the input current is stabilized, the circuit protection device is changed to state (b) so that a normal input current is input to the electrical circuit via the second relay S2.

Since the circuit protection device includes three components including the fuse resistor RF and the first relay S1 and the second relay S2 which have a relatively great volume, costs are high and a larger space is occupied. Also, a normal input current is within a range from 2 A to 4 A in the case of a washer and is 7 A or higher in the case of a dryer. Accordingly, it is necessary to use high-current relays for the first relay S1 and the second relay S2. Here, since the high-current relays are high-priced and there are less commercialized domestic goods, most high-current relays have to be imported from Japan and the like.

In addition, since operations of the first relay S1 and the second relay S2 being opened or closed are repetitively

2

performed whenever an electronic product is turned on or off, as the electronic product is used for a long time, durability thereof decreases and a malfunction occurs. The malfunctions of the first relay S1 and the second relay S2 may cause an inflow of an overcurrent or even cause fire. Accordingly, such risks are inherent all the time in the circuit protection device using relays.

SUMMARY

10

The present invention is directed to providing a circuit protection device capable of replacing a circuit protection device, which includes a fuse resistor RF, a first relay S1, and a second relay S2, as well as reducing costs and less occupying a space without using relays.

15

Aspects of the present invention are not limited to the above-stated aspects and other unstated aspects of the present invention will be understood by those skilled in the art from a following description.

20

According to an aspect of the present invention, there is provided a circuit protection device including a case, a first negative temperature coefficient thermistor which is accommodated in the case and includes a first resistant heating element, a pair of electrodes installed on both sides of the first resistant heating element, and a first lead wire and a second lead wire withdrawn from the pair of electrodes, respectively, a thermal fuse which is accommodated in the case and includes a thermal fuse body and a third lead wire and a fourth lead wire connected to both ends of the thermal fuse body, respectively, and a second negative temperature coefficient thermistor which is accommodated in the case and includes a second resistant heating element, a pair of electrodes installed on both sides of the second resistant heating element, and a fifth lead wire and a sixth lead wire withdrawn from the pair of electrodes, respectively. Here, the second lead wire and the third lead wire are connected to each other and the fourth lead wire and the fifth lead wire are connected to each other in the case.

25

The circuit protection device may further include a first pin connected to the first lead wire and a second pin connected to the sixth lead wire. Here, a first guide groove configured to guide the first pin to be withdrawn outward from the case and a second guide groove configured to guide the second pin to be withdrawn outward from the case may be formed in the case.

30

The first pin and the second pin may include plate-shaped bodies having one sides connected to the first lead wire and the sixth lead wire, respectively, and each include at least one extending portion extending from the other side of the body with a width smaller than that of the body.

35

The bodies of the first pin and the second pin may include first parts having one sides connected to the first lead wire and the sixth lead wire and inserted into the first guide groove and the second guide groove, respectively, and include second parts extending from other sides of the first parts with a width greater than that of the first parts and withdrawn outward from the case.

40

The case may include a partition wall extending from an inner wall of the case and disposed among the thermal fuse body, the first resistant heating element, and the second resistant heating element.

45

The circuit protection device may include a first cable having one end connected to the first lead wire and a second cable having one end connected to the sixth lead wire. Here, a first guide groove configured to guide the first cable to be withdrawn outward from the case and a second guide groove

configured to guide the second cable to be withdrawn outward from the case may be formed in the case.

BRIEF DESCRIPTION OF THE DRAWINGS

The above and other objects, features and advantages of the present invention will become more apparent to those of ordinary skill in the art by describing exemplary embodiments thereof in detail with reference to the accompanying drawings, in which:

FIGS. 1A and 1B illustrate components and operations of an existing circuit protection device;

FIG. 2 is a perspective view of a circuit protection device according to a first embodiment of the present invention;

FIGS. 3A and 3B are cross-sectional views illustrating a first negative temperature coefficient thermistor 20 taken along lines A-A and B-B, respectively;

FIGS. 4C and 4D are cross-sectional views illustrating a second negative temperature coefficient thermistor 40 taken along lines C-C and D-D, respectively;

FIG. 5 is a perspective view illustrating a state in which a case 10 accommodates the negative temperature coefficient thermistors 20 and 40, a thermal fuse 30, and the like which are shown in FIG. 2 and then is filled with a filler;

FIG. 6 illustrates a state in which the circuit protection device according to the first embodiment of the present invention is mounted on a circuit board;

FIG. 7 is a perspective view of a circuit protection device according to a second embodiment of the present invention; and

FIG. 8 is a perspective view illustrating a state in which a case 10 accommodates negative temperature coefficient thermistors 20 and 40, a thermal fuse 30, and the like which are shown in FIG. 7 and then is filled with a filler.

DETAILED DESCRIPTION

Hereinafter, exemplary embodiments of the present invention will be described in detail with reference to the drawings. Hereinafter, throughout the description and the attached drawings, substantially like elements will be referred to as like reference numerals and a repetitive description thereof will be omitted. Also, in a description of the embodiments of the present invention, a detailed description of well-known functions or components of the related art will be omitted when it is deemed to obscure understanding of the embodiments of the present invention.

FIGS. 2 to 5 are views illustrating components of a circuit protection device according to a first embodiment of the present invention. FIG. 2 is a perspective view of the circuit protection device according to the first embodiment. FIGS. 3A and 3B are cross-sectional views illustrating a first negative temperature coefficient thermistor 20 taken along lines A-A and B-B, respectively. FIGS. 4C and 4D are cross-sectional views illustrating a second negative temperature coefficient thermistor 40 taken along lines C-C and D-D, respectively. FIG. 5 is a perspective view illustrating a state in which a case 10 accommodates the negative temperature coefficient thermistors 20 and 40, a thermal fuse 30, and the like which are shown in FIG. 2 and then is filled with a filler.

The circuit protection device according to the first embodiment of the present invention includes the case 10, the first negative temperature coefficient thermistor 20, the thermal fuse 30, the second negative temperature coefficient thermistor 40, a first pin 50_1, and a second pin 50_2.

The case 10 includes, for example, a ceramic material and includes both sidewalls 11 and a front wall 12, a rear wall 13, and a bottom wall 14 so as to form an accommodation groove with an open top in which the first negative temperature coefficient thermistor 20, the thermal fuse 30, and the second negative temperature coefficient thermistor 40 are accommodated. A first guide groove 15_1 and a second guide groove 15_2 are formed on the rear wall 13 to guide the first pin 50_1 and the second pin 50_2 to be withdrawn outward from the case 10, respectively.

As shown in FIGS. 2 to 3B, the first negative temperature coefficient thermistor 20 includes a first resistant heating element 21, a pair of electrodes 22 and 23 installed on both sides of the first resistant heating element 21, a first lead wire 25 and a second lead wire 26 withdrawn from the pair of electrodes 22 and 23, respectively, which are coated with a coating material 24.

A thermistor is a resistor element having a sensitively varying thermal resistance value and particularly has a feature in which an electrical resistance value varies according to a change of a temperature thereof or an ambient temperature. Among such thermistors, a thermistor having a negative temperature coefficient is referred to as a negative temperature coefficient thermistor. The negative temperature coefficient thermistor has a resistance value which decreases according to an increase in a temperature thereof or an ambient temperature.

The thermal fuse 30 includes a thermal fuse body 31 and a third lead wire 32 and a fourth lead wire 33 connected to both ends of the thermal fuse body 31, respectively. Generally, the thermal fuse body 31 includes an insulating ceramic rod having a certain length and a fused body, and the third lead wire 32 and the fourth lead wire 33 may be connected to conductive caps installed respectively on both ends of the ceramic rod.

As shown in FIGS. 2, 4A, and 4B, the second negative temperature coefficient thermistor 40 includes a second resistant heating element 41, a pair of electrodes 42 and 43 installed on both sides of the second resistant heating element 41, a fifth lead wire 45 and a sixth lead wire 46 withdrawn from the pair of electrodes 42 and 43, respectively, which are coated with a coating material 44.

As shown in FIG. 2, the second lead wire 26 of the first negative temperature coefficient thermistor 20 and the third lead wire 32 of the thermal fuse body 30 are connected to each other. The second lead wire 26 may be bent and extend to be connectable to the third lead wire 32 of the thermal fuse 30. Also, the fourth lead wire 33 of the thermal fuse 30 and the fifth lead wire 45 of the second negative temperature coefficient thermistor 40 are connected to each other. The fifth lead wire 45 may be bent and extend to be connectable to the fourth lead wire 33. Connection between the second lead wire 26 and the third lead wire 32 and connection between the fourth lead wire 33 and the fifth lead wire 45 may be performed through soldering, arc welding, spot welding, laser soldering, clamping, or the like.

Meanwhile, the first pin 50_1 and the second pin 50_2, which are conductive materials and connected to a circuit board, are provided to perform electrical connection between a circuit and the circuit protection device. The first pin 50_1 has one end connected to the first lead wire 25 of the first negative temperature coefficient thermistor 20 in the case 10 and extends through the first guide groove 15_1 such that the other end thereof is withdrawn outward from the case 10. The second pin 50_2 has one end connected to the sixth lead wire 46 of the second negative temperature coefficient thermistor 40 in the case 10 and extends through

the second guide groove **15_2** such that the other end thereof is withdrawn outward from the case **10**.

In the embodiment of the present invention, the first pin **50_1** and the second pin **50_2** perform a function of performing electrical connection between the circuit and the circuit protection device, a function of emitting heat generated from the circuit protection device, and a function of spacing the case **10** at a certain interval apart from the circuit board when the circuit protection device is mounted on the circuit board.

The first pin **50_1** and the second pin **50_2** may include plate-shaped bodies **51_1** and **51_2** and extending portions **52_1** and **52_2** which extend from the bodies **51_1** and **51_2** with widths smaller than those of the bodies **51_1** and **51_2**. Generally, the extending portions **52_1** and **52_2** are parts which are inserted into holes of the circuit board and soldered to perform electrical connection, and the bodies **51_1** and **51_2** are parts configured to emit heat and space the case **10** at a certain interval apart from the circuit board.

In detail, the first pin **50_1** may include the body **51_1** having one side connected to the first lead wire **25** and the extending portion **52_1** extending from the other side of the body **51_1** with a width smaller than that of the body **51_1**. The second pin **50_2** may include the body **51_2** having one side connected to the sixth lead wire **46** and the extending portion **52_2** extending from the other side of the body **51_2** with a width smaller than that of the body **51_2**. The first lead wire **25**, the sixth lead wire **46**, and the bodies **51_1** and **51_2** may be connected through soldering, arc welding, spot welding, laser soldering, clamping, or the like.

Also, the bodies **51_1** and **51_2** may include first parts **51a_1** and **51a_2** which have a relatively small width and second parts **51b_1** and **51b_2** which have a relatively great width. Generally, the first parts **51a_1** and **51a_2** are parts connected to the lead wires **25** and **46** and inserted into the guide grooves **15_1** and **15_2**, and the second parts **51b_1** and **51b_2** are parts which are withdrawn outward from the case **10** so as to space the case **10** at a certain interval apart from the circuit board. Also, the second parts **51b_1** and **51b_2** may each include one or more protruding portions **51c** which improve heat dissipation performance.

In detail, the body **51_1** of the first pin **50_1** includes the first part **51a_1** having one side connected to the first lead wire **25** and inserted into the first guide groove **15_1** and the second part **51b_1** extending from the other side of the first part **51a_1** with a width greater than that of the first part **51a_1** and withdrawn outward from the case **10**. The body **51_2** of the second pin **50_2** includes the first part **51a_2** having one side connected to the sixth lead wire **46** and inserted into the second guide groove **15_2** and the second part **51b_2** extending from the other side of the first part **51a_2** with a width greater than that of the first part **51a_2** and withdrawn outward from the case **10**.

Meanwhile, since the negative temperature coefficient thermistors **20** and **40** and the thermal fuse **30** are disposed to be adjacent to one another in a sealed space inside the case **10** such that a temperature of the circuit protection device or an ambient temperature thereof increases, the thermal fuse **30**, which should not be short-circuited, may be short-circuited by heat generation of the negative temperature coefficient thermistors **20** and **40**. Accordingly, a partition wall **16** may be installed among the thermal fuse body **31** and the resistant heating elements **21** and **41** of the negative temperature coefficient thermistors **20** and **40** so as to maintain a certain interval or more among the thermal fuse body **31** and the resistant heating elements **21** and **41**. The partition wall **16** may extend from an inner wall of the case

10, for example, the rear wall **13**. The partition wall **16** is installed not to completely separate spaces in which the resistant heating elements **21** and **41** are accommodated from a space in which the thermal fuse body **31** is accommodated so as to form paths through which the second lead wire **26** and the third lead wire **32** extend and form paths through which the fourth lead wire **33** and the fifth lead wire **45** extend. In one embodiment, the partition wall **16** may include a first partition wall **16a** extending from the rear wall **13** and a second partition wall **16b** extending from an end of the first partition wall **16a** both ways and having a width approximately corresponding to a length of the thermal fuse body **31**.

15 Referring to FIG. 5, the case **10** is filled with a filler **80** while accommodating the negative temperature coefficient thermistors **20** and **40**, the thermal fuse **30**, and the like. The filler **80** not only supports the negative temperature coefficient thermistors **20** and **40** and the thermal fuse **30** inside 20 the accommodation grooves but also enables heat to be effectively dissipated from the negative temperature coefficient thermistors **20** and **40** and the thermal fuse **30**. Accordingly, the filler **80** may include a material having a high heat dissipation property.

25 FIG. 6 illustrates a state in which the circuit protection device according to the first embodiment of the present invention is mounted on a circuit board **P**.

Referring to FIG. 6, extending portions **52** of a pin **50** of 30 a circuit protection device are inserted into to pass through holes **H** formed in the circuit board **P** and soldered so that the circuit protection device is fixed to the circuit board **P** and electrically connected to an electrical circuit on the circuit board **P**. Accordingly, a length **d2** of the extending portions **52** is formed to be greater than a thickness **dP** of the circuit board **P**.

Meanwhile, in the case of an electronic product such as a 35 washer or a dryer to which water is supplied or from which water is generated, the circuit board **P** includes a molding portion **M** having a waterproof material such as urethane and the like to protect the circuit board **P** from water. Since the molding portion **M** is relatively vulnerable to heat, when heat generated from the circuit protection device is transferred directly to the molding portion **M**, the molding portion **M** may be melted and waterproof performance 40 thereof may be degraded. Accordingly, it is necessary to install the case **10** of the circuit protection device to be spaced at a certain interval apart from the circuit board **P** or the molding portion **M**. In the pin **50**, a second part **51b** of 45 a body **51** which is withdrawn outward from the case **10** of the circuit protection device is installed so that the case **10** is spaced at a certain interval apart from the circuit board **P** or the molding portion **M**. The case **10** is spaced as much as a height **d1** of the second part **51b** apart from the circuit board **P**. When a thickness of the molding portion **M** is 50 referred to as **dM**, the case **10** is spaced as much as **d1-dM** apart from the molding portion **M**. Accordingly, **d1** may be greater than **dM**. Also, the molding portion **M** diffuses heat from the circuit protection device so as to assist heat dissipation.

55 FIGS. 7 to 8 are views illustrating components of a circuit protection device according to a second embodiment of the present invention. FIG. 7 is a perspective view of the circuit protection device according to the second embodiment. FIG. 8 is a perspective view illustrating a state in which a case **10** accommodates negative temperature coefficient thermistors **20** and **40**, a thermal fuse **30**, and the like which are shown in FIG. 7 and then is filled with a filler.

In the second embodiment, in comparison to the first embodiment, the first pin **50_1** and the second pin **50_2** are replaced with a first cable **60_1** and a second cable **60_2**, respectively. That is, in the second embodiment, the circuit protection device is implemented not to be installed directly on the circuit board and to be installed separately from a circuit board and connected to a corresponding terminal of the circuit board using the first cable **60_1** and the second cable **60_2**. For convenience, in the second embodiment, a redundant description overlapped with the first embodiment will be omitted.

The first cable **60_1** and the second cable **60_2** include conducting wires **61_1** and **61_2** and coatings **62_1** and **62_2** enclosing the conducting wires **61_1** and **61_2**, respectively. The first cable **60_1** and the second cable **60_2** may be harness cables.

The first cable **60_1** has one end of the conducting wire **60_1** connected to the first lead wire **25** of the first negative temperature coefficient thermistor **20** in the case **10** and extends through the first guide groove **15_1** such that the other end thereof is withdrawn outward from the case **10**. The second cable **60_2** has one end of the conducting wire **61_2** connected to the sixth lead wire **46** of the second negative temperature coefficient thermistor **40** in the case **10** and extends through the second guide groove **15_2** such that the other end thereof is withdrawn outward from the case **10**.

Since the circuit protection device according to the second embodiment is installed separately from the circuit board, there is an advantage in which heat generated at the circuit protection device is not transferred to the circuit board at all.

According to the embodiments of the present invention, since the negative temperature coefficient thermistors **20** and **40** have a resistance value which is great at room temperature or a relatively low temperature and decreases according to an increase in a temperature thereof or an ambient temperature, an inrush current is limited to a certain current using a great resistance value at driving time and a normal input current is maintained using a resistance value decreasing due to an increase in temperature after a certain time. Simultaneously, when the negative temperature coefficient thermistors **20** and **40** are overheated by an overcurrent caused by an abnormal phenomenon in a circuit or an ambient temperature abnormally increases, the thermal fuse **30** short-circuits and cuts off an inflow of current so as to prevent fire. Accordingly, the circuit protection device according to the embodiments can replace an existing circuit protection device shown in FIGS. 1A and 1B. Also, since the negative temperature coefficient thermistors **20** and **40** have a relatively small volume and are low-priced in comparison to high-current relays, a cost of the circuit protection device may be reduced and a space may be less occupied. Also, since relays are not used, it is possible to fundamentally remove a risk element caused by malfunctions of the relays.

A circuit protection device according to the present invention can replace a circuit protection device including a fuse resistor **RF**, a first relay **S1**, and a second relay **S2**. Since the circuit protection device includes a negative temperature coefficient thermistor and a thermal fuse which are low-priced, costs may be reduced. The negative temperature coefficient thermistor and the thermal fuse have a small volume and less occupy a space in comparison to relays. Also, since the relays are not used, it is possible to fundamentally remove a risk of an overcurrent or fire caused by a malfunction of the relays.

The exemplary embodiments of the present invention have been described above. It should be understood by one of ordinary skill in the art that the present invention may be

implemented as a modified form without departing from the essential features of the present invention. Therefore, the disclosed embodiments should be considered not in a limitative view but a descriptive view. The scope of the present invention will be shown in the claims not in the above description, and all differences within an equivalent range thereof should be construed as being included in the present invention.

What is claimed is:

1. A circuit protection device comprising:

a case;
a first negative temperature coefficient thermistor which is accommodated in the case and comprises a first resistant heating element, a pair of electrodes installed on both sides of the first resistant heating element, and a first lead wire and a second lead wire withdrawn from the pair of electrodes, respectively;

a thermal fuse which is accommodated in the case and comprises a thermal fuse body and a third lead wire and a fourth lead wire connected to both ends of the thermal fuse body, respectively;

a second negative temperature coefficient thermistor which is accommodated in the case and comprises a second resistant heating element, a pair of electrodes installed on both sides of the second resistant heating element, and a fifth lead wire and a sixth lead wire withdrawn from the pair of electrodes, respectively;

a first pin comprising a plate-shaped body having one side connected to the first lead wire and at least one extending portion extending from another side of the plate-shaped body of the first pin, wherein a width of the at least one extending portion of the first pin is smaller than that of the plate-shaped body of the first pin; and a second pin comprising a plate-shaped body having one side connected to the sixth lead wire and at least one extending portion extending from another side of the plate-shaped body of the second pin, wherein a width of the at least one extending portion of the second pin is smaller than that of the plate-shaped body of the second pin,

wherein a first guide groove configured to guide the first pin to be withdrawn outward from the case, and a second guide groove configured to guide the second pin to be withdrawn outward from the case are formed in the case, and

wherein the second lead wire and the third lead wire are connected to each other, and the fourth lead wire and the fifth lead wire are connected to each other in the case.

2. The circuit protection device of claim 1, wherein:
the plate-shaped body of the first pin comprises a first part having one side connected to the first lead wire and inserted into the first guide groove, and a second part extending from another side of the first part of the first pin;

a width of the second part of the first pin is greater than that of the first part of the first pin;
the second part of the first pin is withdrawn outward from the case;

the plate-shaped body of the second pin comprises a first part having one side connected to the sixth lead wire and inserted into the second guide groove, and a second part extending from another side of the first part of the second pin;

a width of the second part of the second pin is greater than that of the first part of the second pin; and

the second part of the second pin is withdrawn outward from the case.

3. The circuit protection device of claim 1, wherein the case comprises a partition wall extending from an inner wall of the case and disposed among the thermal fuse body, the first resistant heating element, and the second resistant heating element. 5
